UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed November 5, 1923. Serial No. 672,911.

My invention has relation to means for starting or cranking an engine such as an internal combustion engine, and more particularly to that part of the engine starter system known as the drive or transmission which transmits the power of the prime mover such as an electric motor to a member of the engine to be started such as the flywheel thereof, such drive being capable 5 of manual operation for engagement with the engine member and of automatic disengagement therefrom when the engine operates under its own power. In the practice 10 of my invention, a driving member such as a pinion which is adapted to engage or mesh with the engine member cooperates with a spring adapted to hold such pinion in a normal position upon its shaft, and the object of my invention is to provide 15 means whereby the pressure or tension of this spring may be varied according to the different relative positions of the pinion on its shaft, in particular to lessen the tension 20 of the spring at the time of the disengagement of the pinion from the engine member or fly-wheel when there should be substantially no resistance encountered by the pinion in its longitudinal movement for that 25 purpose.

30 In the drawings, Figure 1 is a sectional elevation of the engine starter system embodying my invention and showing the parts in their normal or disengaged position; Fig. 2 a view similar to Fig. 1 but showing the parts in engaged position; Fig. 3 a section on the line 3-3 of Fig. 1; Fig. 4 a view similar to Fig. 1 but showing the in-board type of installation, and with the parts in disengaged position; and Fig. 5 a 35 view similar to Fig. 4 but illustrating the engaged position of the parts.

Referring to the embodiment of my invention as herein shown, the starter motor 1 is provided with an extended armature shaft 2 having a suitable bearing 3 at its outer end. Upon this driving or armature shaft a hollow shaft or sleeve 4 is mounted for longitudinal movement thereof and for rotary movement therewith, through suitable means such as the longitudinal splines 5 engaged by the bore of the hollow shaft or sleeve. This shaft is provided with a screw threaded portion 6 and may, therefore, be termed a screw shaft. As a sepa-

rate or integral part thereof, the screw 55 shaft is provided at its inner end with parallel flanges 7 forming a circumferential groove 8 with which cooperates the roller 9 on the shifting means. Such shifting means may be of any suitable character and 60 as shown the same consists of a lever 10 pivoted at 11 and actuated by the operator by either foot or hand.

Upon the screw threaded portion of the screw shaft or sleeve is threaded the driving 65 member which is in the form of a pinion 12 adapted to mesh with the engine member or flywheel 13. This pinion is, therefore, mounted upon the screw shaft for rotary movement therewith and for longitudinal 70 movement thereof. It is normally held against the stop nut 14 secured to the outer end of the screw shaft, the same being yieldingly held thereagainst in this normal position in a yielding manner by means of 75 a coil spring 15. This spring encircles the screw shaft and operates against the inner face of the pinion either directly or through the spring cup or retainer 16. The object of the present invention is to provide means 80 whereby the tension of this spring against the pinion may be varied according to the different phases in the cycle of operation of the drive.

To this end, means are provided for shifting the abutment of the inner end of the spring towards and away from the pinion with the result that a maximum or minimum degree of tension or pressure may be exerted by the spring upon the pinion. Specifically 85 such means comprise a longitudinally movable abutment for the inner end of the spring which abutment is controlled according to the different phases of operation by a system of levers under the control of the relative position of the screw shaft upon the armature shaft.

As herein shown, the inner end of the spring cooperates with a longitudinally movable abutment 17 which is in the form of a 100 ring U-shaped in cross section as illustrated in Fig. 1. This ring is adapted to slide longitudinally upon a collar formed in two sections 18, 18 which is secured to the screw shaft in a suitable manner as by means of 105 the screw or dowel pin 19. Between the two sections 18 of this collar, there is interposed and held by the dowel pin 20 a washer 21

having an upwardly extending bracket portion 22 bent outwardly at 23 and provided at its extreme outer end with a pivot pin 24. Upon this pin is pivoted a yoke 25 whose 5 arms are pivoted at 26 to opposite sides of the spring abutment 17. The yoke 25 is actuated by means of a lever or bell crank 27 which is pivoted to the collar 18 on the pivot pin 28 extending across the longitudinal 10 slot 29 in the screw shaft. The elbow of this bell crank is normally positioned upon the periphery 30 of the armature shaft, but when the screw shaft is shifted outwardly longitudinally of the armature shaft, such 15 elbow will ride down upon the slope 31 and upon the reduced portion of the armature shaft between its splines with the result that the upper or free end of the bell crank will be withdrawn from its contact with the yoke 20 25 and thereby permit such yoke and consequently the spring abutment 17 to move inwardly from the position shown in Fig. 1 to the position shown in Fig. 2. Thereupon, the spring 15 which was under some compression when in the normal position shown 25 in Fig. 1 now exerts a minimum or practically no pressure at all against the pinion as shown in Fig. 2.

The pinion is held in a retracted position 30 on the screw shaft by means which form no part of the present invention, but nevertheless will be described as follows: A latch 32 is pivoted upon the pin 28 and has a rearward portion which normally rests upon the 35 shaft periphery 30, but which when the screw shaft is shifted outwardly rides down the slope 31 and thereby permits the outer end of the latch to project upwardly through the slot 29 in position to engage a notch in 40 the bore of the pinion thereby preventing the same from rotating and from being returned by spiral movement to its normal position at the outer end of the screw shaft. The latch 32 is spring pressed in one direction by the 45 spring 33.

Describing a cycle of operation and beginning with the parts in their normal position shown in Fig. 1, the operator actuates the shifting means 10 and thereby shifts the 50 drive assembly outwardly to the position shown in Fig. 2. In this shifting operation, the pinion 12 engages the flywheel 13 and at the same time the bell crank 27, being no longer supported by the armature shaft, will 55 permit the tension of the spring 15 to thrust the abutment 17 inwardly, the yoke 25 oscillating to the position shown in Fig. 2. Consequently, the spring 15 presents a minimum or practically no tension whatever against 60 the pinion 12. As an incident to the operation of the shifting means or as a separate operation, the switch of the motor is operated and current is supplied thereto whereupon the power of the motor will be 65 transmitted to the flywheel and the engine

will be rotated. The pinion will now be demeshed by overrunning the screw threads, the pinion moving longitudinally of the shaft and away from the stop nut. When the pinion comes into the range of the latch 70 32, it will be caught and retained thereby against return in the other direction. At the initiation of this demeshing operation, the tension of the spring is at a minimum and consequently the resistance to demeshing is 75 at a minimum and the catching of the pinion is assured.

After the pinion is demeshed, it will compress the spring in its final longitudinal movement and will be caught by the latch and held in such demeshed position so that such pinion cannot be returned against the now 80 rotating flywheel even if the screw shaft should remain in its outwardly shifted position. Upon the final return movement of the screw shaft, the elbow of the bell crank 27 will ride up the slope 31 and upon the periphery 30 of the armature shaft whereupon the bell crank will oscillate the yoke 25 in an outward direction and move the spring 85 abutment 17 outwardly thereby compressing the spring 15. At the very final movement of the return of the screw shaft, the latch 32 will be actuated and the pinion will thereby be released and the increased tension of 90 the spring 15 will be utilized to spirally move the pinion 12 outwardly and thereby return it to its normal position against the stop nut 14.

As will be obvious, the relationship of the 100 inner end of the latch 32 and the elbow of the bell crank 27 may be varied so that their movement caused by the contacting of the slope 31 may bring about the longitudinal outward movement of the spring abutment 17 either before or after the latch releases the pinion, and the interval may be made any desired amount.

In Figs. 1, 2 and 3, my invention is shown 110 embodied in a drive of the outboard type, that is the type in which the pinion moves outwardly away from the starting motor when meshed with the flywheel and in Figs. 4 and 5, I have shown my invention applied 115 to a drive of the inboard type in which the pinion is moved inwardly towards the starting motor when meshed with the flywheel. The construction and mode of operation are the same in both instances and the same figures of reference are applied to the corresponding parts. However, there is a slight 120 difference over the construction shown in Figs. 1, 2 and 3 in that the periphery 30 and slope 31 are not integral with the armature shaft but are formed by a separate sleeve 34 125 secured to the armature shaft and having a beveled inner end 35 to provide such slope. This sleeve is secured to the armature shaft in a novel manner whereby the same may be readily assembled and disassembled. As 130

shown in Fig. 5, the armature shaft is provided at its outer end with a radial hole or cavity 36 in which slides a pin or plunger 37, spring pressed outwardly by means of a spring 38. The head of this plunger which is of smaller diameter normally projects through a hole 39 in the sleeve 34 with the result that such sleeve is secured to the armature shaft against movement in any direction. The plunger may be pressed inwardly and out of the hole 39 whereupon the sleeve 34 may be readily drawn outwardly and removed from its armature shaft, thereby permitting the entire assembly to be slid off the shaft. There is thus provided simple means permitting of ready assembly and disassembly and of positively locking the parts in place.

I do not herein broadly claim the construction and the arrangement of the drive including the longitudinally shiftable sleeve or driving member or pinion thereon and the catch device for holding the pinion in demeshed position while the screw shaft or sleeve is still shifted to cranking position as the same represent subject matter of my prior applications for patent including application filed on January 4, 1923, Serial No. 610,672, the present application being directed to the particular invention pointed out in the claims herein.

I claim:

1. An engine starter drive including a rotatable shaft, a driving member mounted thereon for rotary movement therewith and for longitudinal movement thereof, yielding means cooperating with the driving member to hold it to a normal position on the shaft, an abutment therefor, and means for shifting the abutment during the operation of the drive to different positions to vary the degree of pressure of such yielding means.

2. An engine starter drive including a rotatable shaft, a driving member mounted thereon for rotary movement therewith and for longitudinal movement thereof, a spring cooperating with the driving member, an abutment therefor, and means for shifting the abutment during the operation of the drive to different positions to vary the degree of pressure of such yielding means.

3. An engine starter drive including a rotatable shaft, a driving member mounted thereon for rotary movement therewith and for longitudinal movement thereof, said shaft being longitudinally movable, yielding means cooperating with the driving member to hold it to a normal position on the shaft, an abutment therefor, and means under the control of the longitudinal movement of the shaft for shifting the abutment to different positions to vary the degree of pressure of such yielding means.

4. An engine starter drive including a rotatable shaft, a driving member mounted

thereon for rotary movement therewith and for longitudinal movement thereof, a spring acting on the driving member tending to hold it to a normal position on the shaft, and means for shifting the spring to different positions according to the position of the driving member relative to the shaft.

5. An engine starter drive including a rotatable shaft, a driving member mounted thereon for rotary movement therewith and for longitudinal movement thereof, a spring acting on the driving member tending to hold it to a normal position on the shaft, an abutment therefor, and means acting on the abutment for bodily shifting it to different positions to vary the degree of pressure of the spring.

6. An engine starter drive including a rotatable shaft, a driving member mounted thereon for rotary movement therewith and for longitudinal movement thereof, a spring acting on the driving member tending to hold it to a normal position on the shaft, an abutment which slides upon the shaft and against which one end of the spring bears, and means for sliding the abutment to vary the degree of pressure of the spring.

7. An engine starter drive including a longitudinally movable rotatable shaft, a driving member mounted thereon for rotary movement therewith and for longitudinal movement thereof, a spring acting on the driving member tending to hold it to a normal position on the shaft, an abutment against which one end of the spring bears, and means controlled by the longitudinal movements of the shaft for shifting said abutment to different positions.

8. An engine starter drive including a longitudinally movable rotatable shaft, a driving member mounted thereon for rotary movement therewith and for longitudinal movement thereof, a spring acting on the driving member tending to hold it to a normal position on the shaft, and means controlled by the longitudinal movements of the shaft for shifting the spring to different positions.

9. An engine starter drive including a longitudinally movable rotatable shaft, a driving member mounted thereon for rotary movement therewith and for longitudinal movement thereof, a spring acting on the driving member tending to hold it to a normal position on the shaft, and means controlled by the longitudinal movements of the shaft for shifting the spring to different positions, said means comprising an abutment and levers cooperating therewith for moving such abutment longitudinally.

10. An engine starter drive including a longitudinally movable rotatable shaft, a driving member mounted thereon for rotary movement therewith and for longitudinal movement thereof, a spring acting on the

- 1 driving member tending to hold it to a normal position on the shaft, and means controlled by the longitudinal movements of the shaft for shifting the spring to different positions, said means comprising a spring abutment in the form of a ring mounted to slide longitudinally on the shaft, a pivoted yoke pivotally connected with the ring, and a lever which is mounted on the shaft and moved in accordance with the longitudinal movements of the shaft, said lever in its movements controlling the movements of the yoke and consequently the position of the ring.
11. An engine starter drive including a longitudinally movable rotatable shaft, a driving member mounted thereon for rotary movement therewith and for longitudinal movement thereof, a spring acting on the driving member tending to hold it to a normal position on the shaft, and means controlled by the longitudinal movements of the shaft for shifting the spring to different positions, said means comprising a spring abutment mounted to slide longitudinally on the shaft, a bracket connected to the shaft, a yoke pivoted to the bracket and to the abutment, and a lever which is pivoted on the shaft and moved in accordance with the longitudinal movements of the shaft, said lever in its movements controlling the position of the yoke and consequently of the abutment.
12. An engine starter drive including a longitudinally movable rotatable shaft, a driving member mounted thereon for rotary movement therewith and for longitudinal movement thereof, a spring acting on the shaft, and means controlled by the longitudinal movements of the shaft for shifting the spring to different positions with respect to the driving member, said means comprising a sleeve secured to one end of the shaft, an abutment against which one end of the spring bears and which slides longitudinally on the sleeve, a yoke pivoted upon the sleeve and pivoted to the ring, and a lever which is pivoted on the shaft and moved in accordance with the longitudinal movements of the shaft, said lever in its movements controlling the position of the yoke and consequently of the abutment.
13. An engine starter drive including a rotatable shaft, a driving member mounted thereon for rotary movement therewith and for longitudinal movement thereof, a spring acting on the driving member tending to hold it to a normal position on the shaft, a driving shaft on which the rotatable shaft is mounted for longitudinal movement thereof and rotary movement therewith, said driving shaft having a sloping annular shoulder towards one end, said rotatable shaft having a longitudinal slot adjacent said shoulder, and means for shifting the spring to different positions with respect to the driving member, such means comprising an abutment in the form of a ring against which one end of the spring bears and which is adapted to move longitudinally with respect to the rotatable shaft, a pivoted yoke pivotally connected to the ring, and a lever pivoted in said slot and controlled in its movements by said shoulder and cooperating with the yoke and consequently the ring to shift them to different positions.
14. An engine starter drive including a rotatable shaft, a driving member mounted thereon for rotary movement therewith and for longitudinal movement thereof, means for holding the driving member in a retracted position on the shaft, yielding means cooperating with the driving member tending to hold it in a normal position on the shaft, an abutment therefor, and means for shifting the abutment to different positions to vary the degree of pressure of such yielding means.
15. An engine starter drive including a driving shaft, a hollow shaft mounted thereon for longitudinal movement thereon and rotary movement therewith, a driving member mounted on the hollow shaft for rotary movement therewith and for longitudinal movement thereof into engagement with a member of the engine to be started and a sleeve fitting upon one end of the driving shaft and having a pin and hole connection with the driving shaft.
16. An engine starter drive including a driving shaft, a hollow shaft mounted thereon for longitudinal movement thereon and rotary movement therewith, a driving member mounted on the hollow shaft for rotary movement therewith and for longitudinal movement thereof into engagement with a member of the engine to be started, a sleeve fitting upon one end of the driving shaft, and a spring pressed pin in the driving shaft, said driving shaft having a hole through which such pin normally extends.
17. An engine starter drive including a rotatable shaft, a driving member mounted thereon for rotary movement therewith and for longitudinal movement thereof, yielding means acting on the driving member tending to hold it to a normal position on the shaft, and means acting during the operation of the drive whereby the degree of pressure of such yielding means is varied.
18. An engine starter drive including a rotatable and longitudinally movable shaft, a driving member mounted thereon for rotary movement therewith and for longitudinal movement thereof, yielding means acting on the driving member tending to hold it toward one end of the shaft, and means acting during the operation of the drive for varying the pressure of such yielding means upon the driving member.

19. An engine starter drive including a rotatable shaft, a driving member mounted thereon for rotary movement therewith and for longitudinal movement thereof, a stop means on the shaft, a yielding means cooperating with the driving member and tending to hold it in normal position against the stop means, and means acting during the operation of the drive whereby the degree of pressure of such yielding means is varied.

20. An engine starter drive including a rotatable shaft, a driving member mounted thereon for rotary movement therewith and for longitudinal movement thereof, a spring cooperating with the driving member and tending to hold it in a normal position on the shaft, and means acting during the operation of the drive whereby the degree of pressure of such spring is varied.

21. An engine starter drive including a rotatable shaft, a driving member mounted thereon for rotary movement therewith and for longitudinal movement thereof, yielding means acting on the driving member tending to hold it to a normal position on the shaft, and means whereby the degree of pressure of such yielding means is varied according to the different positions of the movable parts in the operation of the drive.

22. An engine starter drive including a rotatable shaft, a driving member mounted thereon for rotary movement therewith and for longitudinal movement thereof, means for holding the driving member in a retracted position on the shaft, yielding means acting on the driving member tending to hold it to a normal position on the shaft,

and means whereby the degree of pressure of such yielding means is varied.

23. An engine starter drive including a rotatable shaft, a driving member mounted thereon for rotary movement therewith and for longitudinal movement thereof, a catch device mounted on the shaft in position to engage the driving member and hold it in a retracted position on the shaft, a spring acting on the driving member tending to hold it to a normal position on the shaft, and means whereby the degree of pressure of such spring is varied according to the stage of operation of the parts.

24. An engine starter drive including a rotatable shaft, a driving member mounted thereon for rotary movement therewith and for longitudinal movement thereof, yielding means cooperating with the driving member to hold it to a normal position on the shaft, an abutment therefor, and means responsive to the operation of the drive for shifting the abutment to different positions to vary the degree of pressure of such yielding means.

25. An engine starter drive including a rotatable screw shaft, a pinion threaded thereon for rotary movement therewith and for longitudinal movement thereof, a spring cooperating with the pinion to hold it to a normal position on the shaft, an abutment therefor and means responsive to the operation of the drive for shifting the abutment to different positions to vary the degree of pressure of such spring during a cycle of operation of the drive.

WILLIAM L. McGRATH.
